UNITED STATES PATENT OFFICE

140,620

DESIGN FOR AN OIL BURNER

Henry Weyenberg and Cornelius Quist, Holland,
Mich., assignors to Holland Furnace Company,
Holland, Mich., a corporation of Delaware

Application June 19, 1944, Serial No. 114,101

Term of patent 14 years

(Cl. D81—2)

To all whom it may concern:

Be it known that we, Henry Weyenberg and Cornelius Quist, citizens of the United States, residing at Holland, county of Ottawa, State of Michigan, have invented a new, original, and ornamental Design for an Oil Burner, of which the following is a specification, reference being had to the accompanying drawings, forming a part thereof.

In the drawings:

Fig. 1 is a front elevational view of an oil burner embodying our new design.

Fig. 2 is a fragmentary top plan view of the

same with the barrel broken away for convenience of illustration.

Fig. 3 is a side elevational view of the right side of Fig. 1; and

Fig. 4 is a side elevational view of the left side of Fig. 1.

The dominant features of the design are shown in the drawings in full lines.

We claim:

The ornamental design for an oil burner, substantially as shown and described.

HENRY WEYENBERG.
CORNELIUS QUIST.
